UNITED STATES PATENT OFFICE.

WILLIAM T. BENJAMIN, OF NEWARK, NEW JERSEY, ASSIGNOR TO SHOE MANUFACTURERS' SUPPLY CO., OF NEWARK, NEW JERSEY, A CORPORATION OF NEW JERSEY.

BUTTONHOLE-MARKING MACHINE.

1,101,989.

Specification of Letters Patent. Patented June 30, 1914.

Application filed April 19, 1913. Serial No. 762,187.

To all whom it may concern:

Be it known that I, WILLIAM T. BENJAMIN, a citizen of the United States, residing at 10 Cypress street, Newark, county of Essex, and State of New Jersey, have invented certain new and useful Improvements in Buttonhole-Marking Machines, fully described and represented in the following specification and the accompanying drawings, forming a part of the same.

The present invention relates to a machine for marking the location of buttonholes upon the buttonhole-fly of a shoe, and as the number and distance apart of the buttonholes upon such flies varies greatly with changes of fashion and with the different styles of shoes, the machine requires a special construction for the holders which carry the marking-pins, the means for varying their adjustment, and the means for engaging the position of the fly upon the supporting-plate beneath the marking-pins.

It also relates to a new method of marking flies. In the preferred construction, the crosshead which carries the marking-pins to and from the fly-supporting-plate is preferably made upon its upright face with an undercut groove or other engagement for the holders which carry the marking-pins, and the lazy-tongs which is employed to space the holders proportionally may thus be attached to the holders upon the middle line of their bearing-surface, so that the thrust of the lazy-tongs in separating the holders

operates directly at the point of resistance which is produced by the friction of each holder where it moves upon the crosshead. This construction moves the holders without any tendency whatever to twist them upon their bearing on the crosshead, and it thus avoids unnecessary friction and resulting wear, and prevents the formation of lost motion, which in other machines causes the marking-pins to rock and sway unevenly when the holders are moved, so that they cannot be adjusted and held firmly at a uniform distance apart. In such constructions, the holder at one end of the series is fixed or held stationary upon the crosshead, and the thrust of the lazy-tongs is derived from such stationary holder, and the tongs are moved by a lever and link which expands and contracts the lazy-tongs positively and thus separates or retracts the marking-pins proportionally.

The invention includes the pivoting of a crank-plate upon one end of the holders intermediate the ends of the series, and the connection of crank-pins upon such plate with the holders at opposite ends of the series; a finger-lever being projected from the crank-plate to turn the same when adjusting the marking-pins.

In the present invention, the clamp-segment which is pressed down upon the fly during the marking operation, is provided with a detachable guide-block which can be set upon the upper edge of the segment between any of the marking-pins, and is employed to locate one of the marking-pins adjacent the end of the fly and at a definite distance therefrom. Such guide is used in combination with an adjusting gage upon the fly-supporting-plate so that any number of the pins in the entire series can be adjusted to operate upon the fly and can be set in the proper relation to both of its ends.

The invention will be understood by reference to the annexed drawing, in which—

Figure 1 is a front elevation of the machine; Fig. 2 is a plan of the machine; Fig. 3 is a plan of the clamp and stripper; Fig. 4 is an end view of the machine; Fig. 5 is a cross-section through the post B and rod L on Fig. 2; Fig. 6 is a cross-section through the center of the crank-disk in Fig. 2; Fig. 7 is a perspective view of the gage-block; and Fig. 8 is a perspective view of the gage-block inverted to show its construction.

The bed-plate A of the machine has two round posts B near opposite ends to which a crosshead C is fitted and furnished with rabbeted groove D to receive the feet of the marking-pin-holder E, in which the marking-pins F are held by set-screws G. The crosshead and its rabbeted groove are curved in correspondence with the curved edge of a buttonhole-fly i, lying upon the bed-plate A, as indicated by dotted lines in Fig. 2. The crosshead is moved downward to press the marking-pins into the shoe-flies, a slot A' being formed in the bed to clear the points of the pins. This construction permits the marking-pins to pass entirely through the leather and make an actual perforation. The crosshead is held normally raised by springs C' fitted between the bed and the ends of the crosshead. The usual pull-rod H is attached to the crosshead and extended downward through the bed and

provided with fork I upon the bottom to which a connecting-rod can be attached for depressing the crosshead by a treadle. The fork has a shoulder which limits the upward movement of the crosshead, which is connected by a nut H' to the top of the pull-rod. A curved clamping segment J which acts first as a clamp and then as a stripper at each marking operation, is provided with ears J' to slide upon the posts B and is hung from the crosshead by two rods L attached to lugs M' upon the ears J' and movable through lugs M upon the crosshead, cotter-pins N being fitted through the rods 10 above the latter lugs. Springs K are fitted between the crosshead and stripper. When the crosshead is moved downward the segment J is carried down by the springs K and pressed elastically upon the leather fly 15 i to hold it firmly during the marking operation. The further movement of the crosshead, when the clamp thus rests upon the leather, merely compresses the springs K while the marking-pins F are forced 20 through the leather into the slot A'. The segment acts as a stripper by holding the fly while the pins F are withdrawn.

A special arrangement of the proportional adjuster for the marking-pins is secured by forming the marking-pin-holder E with feet E' fitted to slide snugly in the rabbeted groove D upon the crosshead, and by connecting the joints upon one edge of a lazy-tongs to the said holders on a line 25 about the center of the said feet, so that any separation and retraction of the lazy-tongs 30 operates directly upon the feet and thus move the same without twisting them in the crosshead, which would strain and wear 35 them. This greatly reduces the friction and wear of the feet in the groove D. This results from the application of the force to 40 move the foot, at the middle of its height, so that the upper and lower sides of the 45 feet, which hold the marking-pins in position, are protected almost wholly from wear. The links of the lazy-tongs are marked *a*, the joints connected with the feet of the 50 holder are formed by screws *b*, the joints 55 where the links cross one another, by rivets *c*; and the joints at the free edge of the 60 lazy-tongs by rivets *c'*. The separation and retraction of the holders is effected by a 65 crank or crank-plate *d* jointed upon one of the holder-feet, as shown in Fig. 6, and connected by a link *e* with one of the holders E, preferably at one end of the series. The 70 holder at the end of the series (the right-hand end in Fig. 1) is fixed rigidly in the 75 groove of the crosshead by screw E' and furnishes a fulcrum for the thrust of the 80 lazy-tongs to extend or separate all the 85 holders proportionally, and the crank-plate 90 may be journaled upon such stationary 95 holder or upon one of the movable holders,

which latter arrangement is shown in Figs. 1, 2 and 6. Where only six or eight holders are required in the machine, a crank-plate journaled upon the rigid holder is found to expand the remaining holders uniformly; 100 but where sixteen holders are provided, as shown in Fig. 1, it is found that the holders are moved in a proportional manner more uniformly and perfectly if the crank-plate be located intermediate the ends of the series, and journaled upon one of the movable holders. This condition arises from the fact that in the course of time lost motion may occur in the joints of the lazy-tongs by wear, and such wear prevents the transmission of the expanding motion to all of the 105 holders uniformly, where a large number are moved by propelling the holder at one end of the entire series.

In Fig. 1, the crank-plate is shown journaled upon the sixth holder, and connected by a link *e'* with the stationary holder at the right-hand end of the series, and by a link *e* with the holder at the free end of the series, the fulcra of the holders upon the crank-plate being at distances from the journal of the crank-plate in the proportion of six to ten, so that the first six holders are expanded by the link *e'*; which has no direct connection with the remaining ten 110 holders, which are operated by the link *e* exclusively. It is found that for some reason this connection of the crank-plate with the holders expands them more uniformly than if it were placed upon the middle 115 holder of the series.

To support the crank-plate firmly upon the holder which carries it, such holder, as shown in Fig. 6, has a circular stud *f* projected from the front side of the foot E', 120 upon which the hub of the crank-plate is mounted, a finger-lever *g* being projected upward from the crank-plate to move the same, with the two links. The link *e* is pivoted to the crank-plate at the upper side of the stud *f*, and the link *e'* at the lower side.

It will be noticed that the holders are mounted upon one of the upright sides of the crosshead, by forming the undercut 125 groove D in one of its vertical sides and extending the holders E downwardly therefrom to project the pins F toward the plate A. By this construction, the front of the holder-foot E' is exposed, so that the joints upon one edge of the lazy-tongs can be formed by inserting screws directly in the holder-feet and on a line with the middle of the undercut groove. By this arrangement, the force exerted by the lazy-tongs in moving the various holders between the 130 ends of the series is exerted centrally upon the feet, so as to overcome their frictional resistance in the groove without any tendency to twist the holders against their bearing upon the crosshead, and thus avoiding 135

wear and lost motion. One edge of the groove D is provided with an adjustable gib C' to compensate for wear. It is obviously immaterial whether the groove be formed 5 upon the crosshead or upon the feet, as such a central engagement of the lazy-tongs with each foot can be provided in either case.

The marking-pins F when at rest have their points near the lower edge of the clamp 10 J so that they advance into the leather immediately after the clamp is pressed thereon. When the crosshead rises, the springs K hold the clamp against the fly while the marking-pins are withdrawn therefrom, 15 after moving through the leather into the groove A'; and segment J thus operates to strip the fly off of the marking-pins. The penetration of the marking-pins into the leather is regulated by a gage-screw h extended downward from the crosshead, as shown in Fig. 4, to contact with the top of the bed-plate A when the crosshead is depressed to a suitable point. The construction permits any number of holes to be 20 marked or punched in the shoe-fly i, by adjusting the requisite number of marking-pins at a suitable distance apart for the length of said fly, and regulating such adjustment of the holders by means of a guide-block l. The guide-block is fitted upon the clamping-segment J at the left-hand side of the end marking-pin which is to be used in marking the fly; being shown upon the tenth marking-pin from the first, in Fig. 1. (See 25 Figs. 1, 3, 7 and 8). The guide-block has a foot m to rest upon the top of the clamping-segment J and hold the guide l upon the front side of the same. The foot has a notch n adapted to embrace one of the marking-pins, and flanges o to hold it from displacement, such flanges being readily lifted clear of the clamp J when it is desired to remove the guide-block from any given marking-pin and adjust it upon another. The 30 width of the guide l corresponds with the distance desired from the end of the fly to the first hole, and when the block is adjusted upon the proper marking-pin and the clamp lowered upon the fly, the marking-pins can be readily adjusted by the finger-lever g so that the left-hand edge of the guide coincides with the end of the fly, as 35 in Fig. 1. Such setting of the guide sets the selected marking-pins at a uniform distance apart to mark the holes in the fly in the desired locations.

An end-gage j, shown in Fig. 3, is formed with a foot k to clamp upon the bed adjacent to the stationary marking-pin, and a 40 thumb-screw k' is provided to hold the gage in the desired position when adjusted. Such gage enables the flies to be quickly placed upon the bed in the position desired for marking, and a number of stop-pins o' are 45 set in the bed near the rear edge of the slot

A', against which the convex edge of the fly is placed when the end is set in the angle-gage.

The apparatus is operated by adjusting the end-gage j to suitably set the fly upon 70 the supporting-plate A, with its rear edge against the pins o'. The number of holes to be marked being known, (I have assumed eleven) the guide-block l is set upon the clamp J beyond the last pin required to 75 effect such marking, and the hand-lever g is then moved to bring the outer edge of such guide-block even with the end of the fly i, as shown in Fig. 1. This spaces the eleven pins at a uniform distance apart and makes 80 the end holes at a suitable distance from each end of the fly. The treadle is then depressed, which causes the springs K to first force the clamp down upon the fly and then to press the marking-pins through the 85 leather into the slot A', thus piercing the holes entirely through the fly and marking it with equal distinctness upon both its upper and lower sides. When the treadle is released, the springs C' lift the crosshead, 90 first drawing the marking-pins from the flies and then lifting the clamp so as to permit the removal of the flies from the plate.

Pencil or chalk-markers have often been used in such a marking machine, but the use 95 of a piercing marker permits right and left hand flies to be laid together upon the supporting-plate and pierced at the same time, thus greatly economizing the labor.

The provision of a large number of marking-pin-holders upon the crosshead greatly 100 limits the width of each holder, and as lost motion in their connection with the cross-head permits the points of the pins to wabble and spoils their accurate adjustment, the provision of the adjusting gib C' upon one 105 edge of the groove D is a very great advantage in the construction, as it permits full compensation for any wear of the groove or the holders. This results from the construction of the gib which is made to form the upper half of the groove D, in which the feet E' of the holders are movable. It is customary with such gibs when the groove wears larger than is desirable, to crowd the 110 gib a little closer to the holders to hold them more firmly, which is permitted by the slots through which the gib-screws pass, as shown in Fig. 5.

It will be seen from the above description, 115 that the mechanism furnishes a new method of marking a buttonhole-fly by pointed markers adjustable readily to the different lengths of flies and capable, when desired, of being forced entirely through the leather.

The forcing of the marking-pins through the fly obviously makes the impression as clear upon one side of the fly as upon the other, and thus enables the same setting of 125 the pins and gages upon the bed-plate A to 130

serve for marking either right or left-hand flies; and as the flies for each pair of shoes are right and left, this construction wholly avoids the use of a double machine or of any 5 re-arrangement of the gages or pins for marking one fly or the other. As I am the first to devise a machine in which the marking-pins pass entirely through the fly, I have made special claim to this construction.

10 I have found that stationary stop-pins o' set in the bed near the rear edge of the slot A' may serve satisfactorily to set the edge of the fly during the marking operation, although it may not gage the marking-holes at uniform distances from the edge of the fly. I thus avoid the provision and adjustment of movable gages for the edge of the fly, which arises from the fact that the buttonholes are formed in the fly in a subsequent 15 operation at the points marked, by mechanism which gages the buttonholes at the desired distance from the edge of the fly, and the marking-holes in the fly do not require, therefore, to be made at a uniform 20 distance from the edge of the fly. The stop-pins o' thus secure a material saving in the construction and operation of the machine.

Having thus set forth the nature of the invention what I claim herein is:

30 1. In a buttonhole marking machine, the combination, with a fly-supporting plate, of a crosshead movable to and from the plate, a series of holders adjustable upon the crosshead and the holder at one end secured thereto, piercing marking-pins secured in the 35 holders, a lever pivoted upon one of the intermediate holders, a link connecting such lever with the movable end-holder of the series, and means for moving the crosshead to and from the supporting-plate and forcing the 40 piercing-pins into the slot to fully perforate the fly upon such plate.

2. In a buttonhole marking machine, the combination, with a fly-supporting-plate 45 having the curved slot A' for the passage of piercing-pins, of a crosshead movable to and from the plate and having a series of holders movable thereon over the curved slot and provided with piercing marking-pins, the holder at one end of the series being 50 fixed, a lazy-tongs having the joints pivoted upon the holders, a hand-lever journaled on one of the holders intermediate the ends, connections from such hand-lever to the 55 holder at the movable end of the series, and means for moving the crosshead to and from the supporting-plate.

3. In a buttonhole marking machine, the combination, with a fly-supporting-plate 60 having the curved slot A' for the passage of the piercing-pins, of a crosshead movable to and from the plate and having a series of holders movable thereon over the curved slot and provided with piercing marking-pins, the holder at one end of the series being

fixed, a lazy-tongs having the joints pivoted upon the holders, a double crank journaled upon the lazy-tongs joint on one of the intermediate holders and provided with a handle, links connecting such double crank with the holders at the opposite ends of the series and means for moving the crosshead to and from the supporting plate. 70

4. In a buttonhole marking machine, the combination, with a fly-supporting-plate, of a crosshead movable to and from the same and provided with an undercut groove, a series of marking-pin holders having feet fitted movably to the groove, adjustable connections between the said holders, means for separating them proportionally upon the crosshead and means for moving the crosshead to and from the supporting-plate. 75

5. In a buttonhole marking machine, the combination, with a fly-supporting-plate, of a crosshead movable to and from the same and provided upon one side with an undercut groove, a series of marking-pin holders having feet fitted movably to the groove, proportionally adjustable connections between the said holders the holder at one end of the series being fixed, a lever journaled upon one of the holders intermediate the ends, a link connecting the lever with the holder at the movable end of the series for adjusting the 80 holders, and means for moving the crosshead to and from the supporting-plate. 90

6. In a buttonhole marking machine, the combination, with a fly-supporting-plate, of a crosshead movable to and from the same, a series of marking-pin holders movable upon the crosshead and provided with marking-pins, a clamp-segment suspended movably from the crosshead in close proximity to the marking-pins, and a guide fitted to rest upon the clamp-segment between any two contiguous marking-pins to indicate the setting of the pins in the desired relation to the button-hole-fly, and means for moving the crosshead to and from the supporting-plate. 100

7. In a buttonhole marking machine, the combination, with a fly-supporting-plate, of a crosshead movable to and from the same, a series of holders movable upon the crosshead and provided with marking-pins, a clamp-segment suspended movably from the crosshead in close proximity to the marking-pins, an end-gage upon the plate to set one end of the buttonhole-fly in the desired position, a guide fitted to rest upon the clamp-segment between any two contiguous marking-pins to serve as a gage for setting the marking-pins in relation to the opposite end of the fly and means for moving the crosshead to and from the supporting plate. 110

8. In a buttonhole marking machine, the combination, with the fly-supporting-plate, of a crosshead movable to and from the same, a series of holders movable upon the crosshead and provided with marking-pins, 120

5 a clamp-segment movable to and from the plate adjacent to such pins, a detachable guide-block having a guide to lie between two of the contiguous marking-pins upon the front side of the segment and provided with the foot *m* to rest upon the top of the segment, the foot having a notch adapted to embrace one of the marking-pins, and means for moving the crosshead to and from the 10 supporting-plate.

15 9. In a buttonhole marking machine, the combination, with a fly-supporting-plate, of a crosshead movable to and from the same and having an undercut groove in its upright face, a series of marking-pin-holders having feet fitted movably to the said groove and the 20 holders projected downward from the groove toward the fly-supporting-plate, a lazy-tongs

25 having the joints at one edge connected by screws with the faces of the holder-feet, the holder at one of the series being fixed and one of the holders intermediate the ends of the series having the stud *f* projected therefrom, a crank-plate journaled thereon with finger-lever for turning the same, links *e* and *e'* connecting the crank-plate with the holders at the opposite ends of the series and means for moving the crosshead to and from the supporting-plate.

30 In testimony whereof I have hereunto set my hand in the presence of two subscribing witnesses.

WILLIAM T. BENJAMIN.
